UNITED STATES PATENT OFFICE.

ADELBERT S. JAQUITH, OF BOSTON, MASSACHUSETTS.

DEVICE FOR APPLYING METALLIC LEAF.

1,150,121.

Specification of Letters Patent. Patented Aug. 17, 1915.

Application filed January 11, 1915. Serial No. 1,481.

To all whom it may concern:

Be it known that I, ADELBERT S. JAQUITH, a citizen of the United States, and resident of Boston, in the county of Suffolk and State of Massachusetts, have invented certain new and useful Improvements in Devices for Applying Metallic Leaf, of which the following is a specification.

This invention relates to devices for applying to prepared surfaces to be ornamented, stripes or bands of metallic leaf supplied from a spirally wound supply roll and applied to an adhesive surface by a delivering roll, the device having a handle by which it is manipulated to cause the delivering roll to draw the ribbon of metallic leaf from the supply roll and press it against the prepared surface. In a device of this character the supply and delivering rolls are mounted to rotate between side plates which are separately connected so that the core of the delivering roll may be removed when the ribbon is exhausted and a charged roll inserted and confined. The invention has for its object, first, to provide improved means for locking the two plates in their operative relation to each other, and secondly, to enable the plates to be adjustably spaced apart to accommodate rolls of different lengths and ribbons of different widths.

The invention consists in the improvements which I will now proceed to describe and claim.

Of the accompanying drawing forming a part of this specification: Figure 1 represents a side elevation of a device embodying my invention; Fig. 2 represents a top plan view of the same; Fig. 3 represents a longitudinal section on line 3—3 of Fig. 2; Fig. 3^a represents a perspective view of a portion of one of the plates, hereinafter termed the carrying plate, and its handle-carrying shank; Fig. 3^b represents a perspective view of the carrying plate before the ears are beat down; Fig. 4 represents an edge view of the carrying plate detached from the confining plate hereinafter referred to and provided with roll supporting studs and a handle; Fig. 5 represents an edge view of the confining plate separated from the studs of the carrying plate; Fig. 6 represents a side view of the confining plate; Fig. 7 represents a view similar to Fig. 2, showing each of the carrying plate studs provided with series

of notches and the confining plate provided with means whereby it may be engaged with notches of either series, the supply and delivering rolls being removed; Fig. 8 represents a side view of the confining plate shown by Fig. 7. The same reference characters indicate the same or similar parts in all of the views. In the drawings, 12 represents a carrying plate which is preferably flat sided and relatively thin and is provided at its inner end with an extension which is bent at right angles to the body of the plate to form a handle-carrying shank 13 (Fig. 3^a). Said shank has an orifice 14 adapted to receive a screw 15 which secures the handle 16 to the shank, the shank being also preferably provided with ears 17 at its upper and lower edges, said ears imparting suitable stiffness and rigidity to the shank. To the outer end portion of the carrying plate 12 is rigidly attached an outer stud 18, and to an intermediate portion of the carrying plate is attached an inner stud 19, said studs projecting laterally from the plate and being preferably attached thereto by rivets 20 which may be integral with the studs, inserted in orifices in the carrying plate and upset or headed on the outer surface of said plate. A portion of the inner surface of the carrying plate is offset inwardly to form an annular bearing face 21 against which one end of the supply roll is pressed, as hereinafter described. The studs 18 and 19 are provided with notches in their outer end portions. In the construction shown by Figs. 1 to 5 inclusive, each stud is provided with a single notch 22, and the outer stud 18 is provided with a rigidly attached retaining member or washer 23 between which and the retaining plate the delivering roll 24 is confined, said roll being adapted to rotate on the stud 18. The delivering roll is preferably composed of a metallic core, preferably aluminum, and a compressible facing 24^a of felt or other suitable material, and is provided with a slot 25 adapted to engage the leading end of the paper strip 26 which is wound spirally with the ribbon 27 of metallic leaf on the core 28, which constitutes the body portion of the delivering roll. The paper strip 26 and the ribbon 27 of metallic leaf are wound in alternating convolutions on the core 28 as usual and the core is fitted to rotate on the inner stud 19. During the

operation of applying the metallic leaf to a prepared surface 29, as illustrated by Fig. 3, the paper strip 26 is wound upon the delivering roll, the metallic ribbon being deposited on said surface, which is previously treated with an adhesive.

30 represents the confining plate, which is adapted to be directly and detachably locked to the studs 18 and 19 in the manner next described. The confining plate 30 is of the same general form as the carrying plate 12 and is provided with apertures 31, which are preferably square, as shown by Fig. 6, and are arranged to receive the outer and inner studs 18 and 19. Said apertures are formed to permit an endwise movement of the confining plate relatively to the studs to cause portions of the edges of the apertures 31 to enter the notches 22.

20 In the embodiment of the invention shown by Figs. 1 to 6 the carrying plate is provided with a lever 32 pivoted to said plate at 33, one arm of said lever having an outwardly projecting end or flange 34 and constituting a strut. The other arm of said lever has a projecting wing or handle 35 whereby said strut may be manipulated, as next described.

When the confining plate 30 is detached 30 a charged supply roll is slipped onto the inner stud 19, one end of said roll bearing on the seat 21. The confining plate is then placed upon the outer ends of the studs 18 and 19 and the strut 32 is then swung to the 35 position shown by Fig. 1, its flange 34 being thus caused to bear on the inner stud 19 and force the carrying plate endwise sufficiently to cause portions of the walls of its apertures 31 to enter the notches 22, thus directly 40 locking the confining plate to the two studs, the strut 32 being held in the position shown by Fig. 1 by its frictional engagement with the stud 19. The confining plate is therefore firmly locked in its operative position 45 and the supply roll is securely confined on the stud 19.

To the inner side of the confining plate is attached a friction spring 36, which is a leaf of thin tempered sheet metal, preferably steel, attached at one end by rivets 37 to the plate 30 and bearing loosely and slidingly at its other end on the said plate, the intermediate portion of the spring being bowed inwardly from the plate 30 and provided with a slot 38 (see dotted lines, Fig. 6), which receives the stud 19. The bowed portion and end portions of the springs are relatively wide and are connected by relatively narrow neck portions 39. The spring therefore has a wide bearing on one end of the supply roll and is at the same time rendered sensitive in its action, so that it exerts suitable tension on the supply roll without unduly retarding the rotation of said roll.

65 In the construction thus far described the

delivering roll is permanently confined on the stud 18 between the confining plate 12 and the fixed confining member 23 on said stud. In the construction shown by Figs. 7 and 8 the fixed confining member 23 is omitted and the confining plate designated by 30^a is provided with an offset portion 40 adapted to bear on one end of the delivering roll. Said offset portion may be either integral with the confining plate 30^a or a separate piece or washer. The outer and inner studs 18^a and 19^a are each provided with two series of notches 22^a and 22^b, said notches being in opposite sides of the studs and the notches of one series being in staggered relation with the notches of the other series. The confining plate 30^a is provided with the above described apertures 31 adapted to receive the studs 18^a and 19^a. The confining plate is provided with a double ended 85 strut having two arms 32^a and 32^b of unequal length, said strut being pivoted to the confining plate at 41 and provided with a thumb knob or handle 42. The reversible strut is adapted to bear simultaneously on the studs 18^a and 19^a, and when turned to one position it engages edge portions of the apertures 31 with notches 22^a, and when turned to another position holds edge portions of said apertures in notches 22^b. Provision is thus made for directly locking the confining plate to the studs at different distances from the carrying plate 12 so that the device is adapted to hold a supply roll and a delivering roll of any desired length.

The portions of the shank 13 which form the ears 17 are preferably provided with tongues 17^a (Fig. 3^b), and the plate 12 is preferably provided with recesses 12^a which receive said tongues, as shown by Fig. 3^a, when the ears 17 are bent to place. The tongues may be upset at their outer ends after their insertion in the sockets, so that they constitute rivets securely connecting the ears 17 with the plate 12, the ears bearing on the inner side of said plate. The confining plate 30 in the embodiment of the invention shown by Figs. 1 to 6 is formed at its inner end to bear on the shank 13 at its ears.

Having described my invention, I claim:

1. A device of the character stated, comprising a carrying plate having a laterally projecting handle-carrying shank at its inner end and laterally projecting outer and inner studs, one at the outer end portion and the other at an intermediate portion of said plate, a delivering roll journaled on the outer stud, a confining plate provided with apertures formed to receive the studs and to permit its endwise movement thereon, said studs being provided with notches, means carried by the confining plate for engaging one of said studs and thereby mov-

ing the confining plate endwise to enter edge portions of its apertures into said notches and thus directly lock the confining plate to each of the studs, and a supply roll journaled on the inner stud and removably confined thereon by the carrying and securing plates.

2. A device of the character stated, comprising a carrying plate having a laterally projecting handle-carrying shank at its inner end and laterally projecting outer and inner studs, one at the outer end portion and the other at an intermediate portion of said plate, a delivering roll journaled on the outer stud, a confining plate provided with apertures formed to receive the studs and to permit its endwise movement thereon, said studs being provided with notches, a swinging strut pivoted to the confining plate and movable into engagement with one of said studs, to move the confining plate endwise and thereby enter edge portions of its apertures into said notches and thus directly lock the confining plate to each of the studs, and a supply roll journaled on the inner stud and removably confined thereon by the carrying and securing plates.

3. A device of the character stated, comprising a carrying plate having a laterally projecting handle-carrying shank at its inner end and laterally projecting outer and inner studs, one at the outer end portion and the other at an intermediate portion of said plate, a delivering roll journaled on the outer stud, a confining plate provided with apertures formed to receive the studs and to permit its endwise movement thereon, said studs being provided with notches, a swinging strut pivoted to the confining plate and movable into engagement with one of said studs, to move the confining plate endwise and thereby enter edge portions of its apertures into said notches and thus directly lock the confining plate to each of the studs, and a supply roll journaled on the inner stud and removably confined thereon by the carrying and securing plates, each stud being provided with a series of notches whereby the confining plate may be locked at different distances from the carrying plate.

4. A device of the character stated, comprising a carrying plate having a laterally projecting handle-carrying shank at its inner end and laterally projecting outer and inner studs, one at the outer end portion and the other at an intermediate portion of said plate, a delivering roll journaled on the outer stud, a confining plate provided with apertures formed to receive the studs and to permit its endwise movement thereon, said studs being provided with notches, a swinging strut pivoted to the confining plate and movable into engagement with one of said studs, to move the confining plate endwise and thereby enter edge portions of its

apertures into said notches and thus directly lock the confining plate to each of the studs, and a supply roll journaled on the inner stud and removably confined thereon by the carrying and securing plates, each stud being provided with two series of notches, one series in staggered relation to the other, and the strut being reversible and adapted to engage either of said studs.

5. A device of the character stated, comprising a carrying plate having a laterally projecting handle-carrying shank at its inner end and laterally projecting outer and inner studs, one at the outer end portion and the other at an intermediate portion of said plate, a delivering roll journaled on the outer stud, a confining plate apertured to receive said studs, a supply roll removably journaled on the inner stud, said studs and confining plate being provided with complementary devices for directly locking the confining plate to each of the studs, and a friction spring attached at one end to the confining plate and in sliding contact therewith at its other end, the intermediate portion and end portions of the spring being widened and the intermediate portion curved to bulge inwardly between its ends and bear with a yielding pressure on one end of the supply roll, the intermediate portion being connected with the end portions by relatively narrow necks.

6. A device of the character stated, comprising a carrying plate having a laterally projecting handle-carrying shank at its inner end, said shank being provided with bent ears bearing on the inner side of the plate, laterally projecting outer and inner studs attached to said plate, a delivering roll journaled on the outer stud, a confining plate apertured to receive said studs, and a supply roll removably journaled on the inner stud, said studs and confining plate being provided with complementary devices for directly locking the confining plate to each of the studs.

7. A device of the character stated, comprising a carrying plate having a laterally projecting handle-carrying shank at its inner end, said shank being provided with bent ears bearing on the inner side of the plate, laterally projecting outer and inner studs attached to said plate, a delivering roll journaled on the outer stud, a confining plate apertured to receive said studs and formed to bear on said shank and its ears, and a supply roll removably journaled on the inner stud, said studs and confining plate being provided with complementary devices for directly locking the confining plate to each of the studs.

8. A device of the character stated, comprising a carrying plate having a laterally projecting handle-carrying shank at its inner end, the shank being provided with bent

ears bearing on the inner side of said plate and having tongues, and the plate being provided with sockets receiving said tongues, laterally projecting outer and inner studs attached to said plate, a delivering roll journaled on the outer stud, a confining plate apertured to receive said studs, and a supply roll removably journaled on the inner stud, said studs and confining plate being provided with complemental devices for directly locking the confining plate to each of the studs.

9. A device of the character stated, comprising a carrying plate having a laterally projecting handle-carrying shank at its inner end, the shank being provided with bent ears bearing on the inner side of said plate and having tongues, and the plate being pro-

vided with sockets receiving said tongues, laterally projecting outer and inner studs attached to said plate, a delivering roll journaled on the outer stud, a confining plate apertured to receive said studs and formed to bear on said shank and its ears, and a supply roll removably journaled on the inner stud, said studs and confining plate being provided with complemental devices for directly locking the confining plate to each of the studs.

In testimony whereof I have affixed my signature, in presence of two witnesses.

ADELBERT S. JAQUITH.
